ABRADING DEVICE

Alfred V. Breed, Jamestown, N. Y., assignor to
 Curtis Machine Corporation, Jamestown, N. Y.,
 a corporation of New York

Application July 30, 1937, Serial No. 156,523

6 Claims. (Cl. 51—141)

This invention relates to an improvement in abrading or polishing devices for flat material, and particularly to that class of devices having an endless abrading belt movable into and out 5 of contact with the material to be polished.

One form of the invention is shown applicable to an abrading or polishing machine which is provided with an endless abrading belt adapted to be moved into contact with a given material 10 for the purpose of smoothing and polishing the surface thereof. The device is known as a polishing head and supports a shoe or roller for manual vertical movement to contact the abrading belt and move it into contact with the mating belt and move it into contact with the material. The polishing head is mounted on a carriage which in turn is supported on a track that extends substantially parallel with the direction of travel of the belt and the polishing head and shoe are, therefore, capable of movement with 15 respect to the material to be worked upon.

Prior to this invention it has been the practice to provide a polishing device of the general class to which this invention relates with an extremely heavy and rugged polishing head, this 20 being considered necessary to prevent flexing, bending, or misalignment of the polishing member in order that the material might be properly surfaced. Since many of these polishing heads were of an extremely rugged nature they required a rather unwieldly manual operating structure. In fact, the operating structure was such that it has, in the past, been extremely difficult to depress a polishing member and abrading belt into exactly the proper degree of 25 pressure contact with the surface of the material for the purpose of removing blemishes, spots, or unevenness in a given surface. It is quite evident that the surfaces of materials may have blemishes or imperfections of varying size and depth, and consequently, the polishing head should be very sensitive to control by the operator if it is desired to avoid producing a wavy and uneven finish.

The invention is, therefore, directed to and 30 has for its objects the provision of a polishing head for an abrading device which is of extremely simple and rugged construction and which is adaptable for use in connection with both rough and finish polishing. Due to the fact 35 that there are relatively few moving parts, full manual control of the pressure with which an abrading belt may contact the surface of a given material is possible.

Other and further objects and advantages of 40 the invention will be more fully understood

from a consideration of the following specification taken in conjunction with the accompanying drawing and in which:

Fig. 1 is a front elevation of one form of a 5 polishing head embodying the invention;

Fig. 2 is an enlarged vertical sectional view of the polishing head; and

Fig. 3 is a horizontal sectional view taken substantially on the lines 3—3 of Fig. 2.

Referring to the drawing, the reference numeral 10 is employed to generally indicate a polishing head for an abrading device. The head consists of a housing 11 which may, as shown in the drawing, be formed integral with a carriage 12. The carriage 12 is adapted to be laterally movable over a track 13 through provision of a number of rollers. Although the number and arrangement of rollers may be varied as needed, the present disclosure includes top and bottom rollers 14 and 15. These rollers are suitably mounted on shafts which are in turn mounted on portions 16. Rollers 14 are adapted to ride on the upper edge of track 13 and rollers 15 along the under edge of the track. Projecting beyond the ends of the carriage 12 are arms 18. Each of these arms mounts a roller 19 which is adapted to contact one vertical face of the track 13. Referring to Figure 2 of the drawing, it will be noted that the carriage 12 includes a portion 21 which is formed with a horizontally extending recess 22 approximately the width and depth of the track 13 and is adapted to receive said track. Secured to the carriage 12 directly above and below the recess 22 are angle members 23. These members are pivotal about pins 24 and at their outer ends are fitted with rollers 26 which are adapted to engage the vertical surface of the track 13 opposite to the surface engaged by rollers 19. A rod 27 is threaded at its ends and engageable with threaded opening in 30 each of the angle members 23. Provision of oppositely directed threads on the rod 27 causes it when rotated to pivot the members 23 about their pins 24 and move rollers 26 into or out of contact with the track 13.

The housing 11 is generally cylindrical and, in the present illustration, assumes a vertical position. The housing is formed with a full length cylindrical opening 28. A cap 29 closes the upper end of the opening 28 of the housing, being secured thereto in any suitable manner as by screws 30. The cap 29 is formed with a bearing portion 31 which projects into the opening 28 and throughout a part of its length closely fits the walls of said opening. A cylindrical opening 32

45

50

55

55

is formed in the portion 31, thus causing said portion to be in the nature of a sleeve within the housing. A shaft 33 having a length greater than the length of the housing 11 projects thereinto, one end being located within the opening 32 of the portion 31. A collar 34 of a diameter slightly less than that of the opening 28 is secured to the shaft in any suitable manner as by a pin 36. The collar 34 may be formed with an annular shoulder 37 which is adapted to serve as a seat for one end of a coil spring 38 that encircles a portion of the shaft 33 beneath the collar. The lower end of the housing 11 is provided with a cap 39 which is secured thereto by screws 41. The cap 39 is formed with a portion 42 which projects into and closely fits the walls of the opening 28. An opening 43 is made through the cap 39, through which the lower end of the shaft 33 projects. Formed in the shaft 33 is a keyway 44. A key 46 projects into the keyway 44 and in the instant disclosure takes the form of a screw having threaded engagement with the portion 42 of the cap 39. It will be understood that the shaft 33, although movable outwardly of the housing 11 against tension of the spring 38, is prevented rotation by reason of the key and keyway.

Secured to the end of the shaft 33 projecting beneath the lower cap 39 is a member 47 which 30 serves to couple shaft 33 with a further shaft 48. The lower end of shaft 48 is joined to a bracket 49 having a central opening 51. Bracket 49 is fitted with opposed thumb screws 52, the inner ends of which may be projected into the opening 51. A 35 pin or bolt 53 pivotally joins a polishing member 54 to the bracket 49. The upper end 55 of the polishing member projects into the opening 51 and is contacted by the ends of screws 52. Thus adjustment of screws 52 pivots the polishing member 54 about pin 53.

A pair of ledges or shoulders 57 are formed 45 midway of the length of the housing 11 and are provided with openings to receive pivot pins. An operating lever 58 terminates in a forked end 59 which is adapted to fit the housing. The arms 61 of the fork abut shoulders 57 and are pivotally joined thereto by the pins heretofore mentioned. The other end of the operating lever is provided with a suitable knob 62. Substantially midway 50 of the length of the lever 58 a pair of spaced downwardly projecting lugs 63 are formed. These lugs have concentric openings through which a pin 64 projects to secure a link 66. This link is joined to a further link 67 by a bolt 68. The 55 openings through which bolt 68 projects in the links 66 and 67 are in the form of slots to facilitate altering the combined length of these links. The lower end of link 67 terminates in a fork 69 which receives a lug 71 formed on the collar 47. A pin 72 projects through concentric openings in 60 the fork 69 and lug 71 to pivotally secure the link 67 to the collar 47.

In operation a sheet of material 73 is mounted 65 on the bed (not shown) of an abrading device which includes the polishing head above described. An endless belt 74 is caused to move continuously in one direction slightly above the material 73. The polishing member 54 includes a shoe 76 which is adapted to be moved into contact with the belt 74 and cause said belt to contact the surface of the material 73. The operator grasps the knob 62 of the operating lever 58 and moves the polishing head along the track 70 75 13 to a position directly over that portion of the

material 73 it is desired to polish. When the operating lever is moved downwardly about its pivotal connection with housing 11, links 66 and 67 cooperate to move collar 47, member 54, and shoe 76 downwardly. The direction of movement of these elements is controlled by the shaft 33 which moves downwardly of the housing 11 and compresses spring 38. The tension of spring 38 is insufficient to cause too great an effort on the part of the operator to lower the shoe 76 into contact with the belt 74 and yet produces sufficient tension so that upon releasing the operating lever 58 the belt 74 will immediately withdraw from the surface of the material 73.

It will be noted that the polishing head 15 described consists of a rod within a closed housing, which housing is provided with end bearings adequate to support the rod against all lateral thrust. Furthermore, no problem exists in lubricating the rod 33 since the compartment or opening 28 in 20 the housing 11 is sealed and may be packed with grease or other suitable lubricant. This phase of the present invention is of particular value inasmuch as polishing and abrading devices when in use produce a considerable quantity of dust and 25 grit which ordinarily would get into the working parts of the head and affect the operation thereof.

Although applicant has shown and described only one modification of the invention, it will be understood by those skilled in the art that other 30 modifications or adaptations of the structure may be made and are contemplated insofar as such modifications are within the spirit and scope of the invention as defined in the hereunto annexed claims.

Having thus set forth my invention what I 35 claim as new and for which I desire protection by Letters Patent is:

1. A polishing head for an abrading device including a track mounted carriage, a housing 40 on said carriage, an axially movable shaft projecting into said housing, a cap closing one end of said housing, means forming a part of said cap projecting into said housing, said means being engaged with and adapted to mount one 45 end of said shaft, spring means normally sustaining said shaft in said housing, a polishing member joined to one end of said shaft, and means operable to withdraw said shaft from said housing in opposition to said spring means where- 50 by to move said polishing member into position of use.

2. A polishing head for an abrading device having an open ended housing, an axially movable shaft projecting into said housing, a cap closing 55 one end of said housing, a bearing portion on said cap located within said housing, said portion mounting one end of said shaft in all positions thereof, spring means normally sustaining said shaft in said housing, a polishing member joined 60 to one end of said shaft, and means operable to partially withdraw said shaft from said housing in opposition to said spring means whereby to move said polishing member into position of use.

3. A polishing head for an abrading device 65 having a housing open at opposite ends, a shaft projecting into said housing, a cap closing one end of said housing, means adjacent said cap adapted to mount one end of said shaft, a further cap closing the other end of said housing, 70 bearing means in said further cap mounting said shaft, spring means in said housing engaged with and normally supporting said shaft, a polishing member joined to one end of said shaft, and means operable to axially move said shaft in 75

opposition to said spring means whereby to move said polishing member into position of use.

4. A polishing head for an abrading device having a housing open at opposite ends, a shaft projecting into said housing, a cap closing one end of said housing, a bearing portion on said cap located within said housing, said portion being engaged with and adapted to mount one end of said shaft in all positions thereof, a further cap closing the other end of said housing, said further cap having an opening therethrough for receiving said shaft, a spring in said housing engaged with and adapted to normally support said shaft, a polishing head joined to one end of said shaft, and means operable to axially move said shaft in a direction to compress said spring whereby to move said polishing member into position of use.

5. A polishing head for an abrading device including a housing open at opposite ends, caps closing the ends of said housing, bearing means in said caps, an axially movable shaft mounted in said bearing means, a spring in said housing engaged with and normally supporting said shaft,

a polishing member joined to one end of said shaft, an operating lever pivotally secured to said housing, means connecting said lever with a member joined to said shaft whereby movement of said lever will axially move said shaft in opposition to said spring and adjust said polishing member. 5

6. A polishing head for an abrading device including a housing, bearing means in said housing, said means projecting beyond the ends of 10 and serving to close said housing, an axially movable shaft projecting into said housing, spring means engaged with and supporting said shaft in said housing, a member joined to one end of said shaft, a polishing member, said first mentioned member serving to couple said shaft with said polishing member, means on said polishing member for varying the angular position thereof with respect to said shaft, and further means operable to withdraw said shaft from said housing 15 20 in opposition to said spring means whereby to move said polishing member into position of use.

ALFRED V. BREED.
